LPA(57) **CLAIM**

The ornamental design for a "UV radiation apparatus," as shown and described.

DESCRIPTION

FIG. 1 is a top plan view;

FIG. 2 is a bottom plan view;

FIG. 3 is a front view;

FIG. 4 is a rear view;

FIG. 5 is a side view;

FIG. 6 is another side view;

FIG. 7 is a perspective view; and,

FIG. 8 is another perspective view thereof.
